THE INVENTION RELATED TO THE PRESENT INVENTION IS APPARENTLY RELATED TO THE INVENTION OF THE SAME INVENTOR, TITLED "DOOR HANDLE ASSEMBLY", SERIAL NO. 35,320, FILED JUNE 26, 1948, AND IS APPARENTLY RELATED TO THE INVENTION OF THE SAME INVENTOR, TITLED "DOOR HANDLE ASSEMBLY", SERIAL NO. 35,321, FILED JUNE 26, 1948.

UNITED STATES PATENT OFFICE

2,651,537

ESCUTCHEON FOR DOORS

Edwin Ewald, Detroit, Mich., assignor to Automotive Appliance Company, Detroit, Mich., a partnership

Application November 15, 1949, Serial No. 127,404

1 Claim. (Cl. 292—357)

1 The present invention relates to an improved escutcheon, and the present application is a continuation-in-part of the copending application of Edwin Ewald, Serial No. 35,320, filed June 26, 1948, now abandoned. The present invention relates to an escutcheon which is employed with a handle, particularly for use in automobiles, and in which the escutcheon covers the opening in the panel through which the shaft of the operating mechanism projects.

One of the primary objects of the present invention is to provide an economical escutcheon which facilitates the installation or removal of a handle or the like associated with it.

Another object of the invention is to provide an improved escutcheon which is formed of a nonmetallic flexible material so that the member may be compressed or shortened axially for easy assembly or disassembly of the handle.

A further object of the invention is to provide an improved escutcheon construction having proper bearing relationship with movable handle parts, but at the same time having a good frictional engagement with the adjacent panel or upholstery so that the handle is free to move relative to the escutcheon, but the escutcheon does not move relative to the panel.

Other objects of the present invention will become apparent from the following specification, the drawing relating thereto, and from the claim hereinafter set forth.

In the drawing in which like numerals are used to designate like parts in the several views throughout:

Figure 1 is an elevational view taken substantially in the direction of the arrows 1—1 of Fig. 2;

Fig. 2 is a side elevational view with parts in cross section, taken substantially through the center of the escutcheon, and showing the escutcheon and handle in their final assembled relationship;

Fig. 3 is a partial view, similar to Fig. 2, but illustrating a different relative position of the escutcheon with respect to the handle for assembly or disassembly thereof;

Fig. 4 is a perspective view toward the inner or under side of the escutcheon; and

Fig. 5 is a perspective view of the escutcheon from the outer side.

Referring to the drawing, the invention is illustrated in connection with the inside door handle of an automobile, but it will be appreciated that it is equally useful on the outside of the door and on other panels.

An inner door panel is indicated at 1, and such

panel has a recessed portion 2 formed therein for receiving a handle 5. The escutcheon 10 is provided with a central opening 12 which is circular in cross section and which is defined by the inner periphery of the escutcheon 10 and the outer periphery of a bearing member 16 disposed within the opening 12. The bearing member 16 terminates in an outwardly directed, annular flange 17 which overlies the outer surface of the escutcheon member 11 adjacent

the corner of opening 13. The bearing member 16 is disposed within the opening 13 and is secured to the escutcheon member 11.

The escutcheon member 11 is provided with a recessed portion 13 which is circular in cross section and which is defined by the outer periphery of the bearing member 16 and the inner periphery of the escutcheon member 11.

The escutcheon member 11 is provided with a recessed portion 14 which is circular in cross section and which is defined by the outer periphery of the bearing member 16 and the inner periphery of the escutcheon member 11.

The escutcheon member 11 is provided with a recessed portion 15 which is circular in cross section and which is defined by the outer periphery of the bearing member 16 and the inner periphery of the escutcheon member 11.

The escutcheon member 11 is provided with a recessed portion 16 which is circular in cross section and which is defined by the outer periphery of the bearing member 16 and the inner periphery of the escutcheon member 11.

The escutcheon member 11 is provided with a recessed portion 17 which is circular in cross section and which is defined by the outer periphery of the bearing member 16 and the inner periphery of the escutcheon member 11.

The escutcheon member 11 is provided with a recessed portion 18 which is circular in cross section and which is defined by the outer periphery of the bearing member 16 and the inner periphery of the escutcheon member 11.

The escutcheon member 11 is provided with a recessed portion 19 which is circular in cross section and which is defined by the outer periphery of the bearing member 16 and the inner periphery of the escutcheon member 11.

The escutcheon member 11 is provided with a recessed portion 20 which is circular in cross section and which is defined by the outer periphery of the bearing member 16 and the inner periphery of the escutcheon member 11.

The escutcheon member 11 is provided with a recessed portion 21 which is circular in cross section and which is defined by the outer periphery of the bearing member 16 and the inner periphery of the escutcheon member 11.

The escutcheon member 11 is provided with a recessed portion 22 which is circular in cross section and which is defined by the outer periphery of the bearing member 16 and the inner periphery of the escutcheon member 11.

The escutcheon member 11 is provided with a recessed portion 23 which is circular in cross section and which is defined by the outer periphery of the bearing member 16 and the inner periphery of the escutcheon member 11.

The escutcheon member 11 is provided with a recessed portion 24 which is circular in cross section and which is defined by the outer periphery of the bearing member 16 and the inner periphery of the escutcheon member 11.

The escutcheon member 11 is provided with a recessed portion 25 which is circular in cross section and which is defined by the outer periphery of the bearing member 16 and the inner periphery of the escutcheon member 11.

The escutcheon member 11 is provided with a recessed portion 26 which is circular in cross section and which is defined by the outer periphery of the bearing member 16 and the inner periphery of the escutcheon member 11.

The escutcheon member 11 is provided with a recessed portion 27 which is circular in cross section and which is defined by the outer periphery of the bearing member 16 and the inner periphery of the escutcheon member 11.

The escutcheon member 11 is provided with a recessed portion 28 which is circular in cross section and which is defined by the outer periphery of the bearing member 16 and the inner periphery of the escutcheon member 11.

The escutcheon member 11 is provided with a recessed portion 29 which is circular in cross section and which is defined by the outer periphery of the bearing member 16 and the inner periphery of the escutcheon member 11.

The escutcheon member 11 is provided with a recessed portion 30 which is circular in cross section and which is defined by the outer periphery of the bearing member 16 and the inner periphery of the escutcheon member 11.

The escutcheon member 11 is provided with a recessed portion 31 which is circular in cross section and which is defined by the outer periphery of the bearing member 16 and the inner periphery of the escutcheon member 11.

The escutcheon member 11 is provided with a recessed portion 32 which is circular in cross section and which is defined by the outer periphery of the bearing member 16 and the inner periphery of the escutcheon member 11.

The escutcheon member 11 is provided with a recessed portion 33 which is circular in cross section and which is defined by the outer periphery of the bearing member 16 and the inner periphery of the escutcheon member 11.

The escutcheon member 11 is provided with a recessed portion 34 which is circular in cross section and which is defined by the outer periphery of the bearing member 16 and the inner periphery of the escutcheon member 11.

The escutcheon member 11 is provided with a recessed portion 35 which is circular in cross section and which is defined by the outer periphery of the bearing member 16 and the inner periphery of the escutcheon member 11.

The escutcheon member 11 is provided with a recessed portion 36 which is circular in cross section and which is defined by the outer periphery of the bearing member 16 and the inner periphery of the escutcheon member 11.

The escutcheon member 11 is provided with a recessed portion 37 which is circular in cross section and which is defined by the outer periphery of the bearing member 16 and the inner periphery of the escutcheon member 11.

provides a metal bearing between it and the adjacent surface of the flange 6, and also provides a bearing between the outer surface of the annular flange 17 and the adjacent surface of the handle 5.

Figs. 2 and 3 illustrate the manner in which the handle may be assembled or disassembled. For assembly the escutcheon 10, including both the flexible member 11 and the metal collar 16, is positioned over the projecting end of the stem 2. The handle 5 is then positioned over the projecting end of the stem 2 so that the flange 6 is received within the axial opening of the collar 16. The stem 2 is received within the opening 4 of the handle 5 so that openings 7 and 8 are in alignment. The escutcheon 11 may then be compressed or shortened axially, as shown in Fig. 3, so that the outer end of one of the openings 7 is exposed. The pin 9 may then be inserted through the aligned openings 7 and 8. The pin 9 is of such a length that it does not project beyond the peripheral surface of the flange 6 and the resilient escutcheon 11 will, upon being released, return to its normal position as shown in Fig. 1. The pin 9 cannot then become inadvertently displaced because it is held against axial movement by the collar 16. At the same time, the collar 16 will permit easy relative movement between the handle 5, and the escutcheon 10, and in any position the pin 9 is prevented from moving out of its locking position. However, the handle may be easily removed by again shortening it to the position shown in Fig. 3 and pushing the pin 9 out.

Formal changes may be made in the specific embodiment of the invention described without departing from the spirit of the present invention, the scope of which is commensurate with the appended claim.

What is claimed is:

An escutcheon structure comprising a non-metallic flexible member of generally truncated conical form open at its ends with a relatively smaller opening at one end, said flexible member having an integral flange within said smaller opening and extending axially thereof, said flexible member being compressible axially thereof so that the end having the smaller opening may be moved toward the opposite end, reinforcing ribs formed integral with said flexible member internally thereof, and a metal collar disposed within the smaller opening and extending over said flange, said metal collar having a flange extending outwardly over the outer periphery of said smaller opening.

EDWIN EWALD.
